ABSTRACT OF THE DISCLOSURE

An antibacterial amount of certain dipeptides of histidine is administered to mammals in need of an antimicrobial effective in protecting against cocci and bacilli.

BACKGROUND OF THE INVENTION

This is a continuation-in-part of Ser. No. 697,002, filed Jan. 11, 1968, now abandoned. The invention pertains to antimicrobials. In a particular aspect this invention relates to antimicrobials effective in protecting against bacterial infections caused by cocci and bacilli.

Bacteria such as cocci and bacilli are organisms embodying within themselves an array of yet unanswered puzzles in biology, both fundamental and experimental. They are ubiquitous in distribution and have attained extreme degrees of diversification in biological and biochemical characteristics. It is recognized that the significance of staphylococcal infections is not so much in severity, except in a few instances, as in the subtleties of the infection due to the unpredictable vagaries of these organisms.

Treatment of staphylococcal diseases is complicated by the ability of the organisms to develop resistance. The magnitude of the problem is further amplified by the extreme difficulty of total eradication, and the frequent re-appearance of the same strain even after apparently successful elimination. The inability to eliminate the carrier state by any of the currently known methods and the prevalence of the new anti-biotic resistant hospital strains have added a new dimension to the frustrating situation.

Penicillin G (benzyl penicillin) is still the drug of choice for the treatment of infections caused by susceptible coccic strains. However numerous strains are known which elaborate an enzyme penicillinase in response to the drug and thus remain insensitive. This led to the development of semi-synthetic penicillins which are not inactivated by penicillinase. However recently resistance of staphylococci to the newer penicillins has been reported. Hence there is a seemingly never ending demand for anti-coccic factors.

A variety of substances are reported which alter host resistance to coccic infections. However, drugs which induce a high degree of resistance to coccic infections are not in wide use. In addition drugs which confer immunity to coccic infections for more than a week after administration are virtually unknown. In one of its aspects this invention provides an antimicrobial for the treatment of staphylococcal and bacillic infections. By another aspect of this invention is to give immunity to reinfection.

SUMMARY OF THE INVENTION

The dipeptide of beta-alanine and histidine known as carnosine, and its homolog the dipeptide of gamma-aminobutyric acid and histidine, known as homocarnosine, have been identified in the brains of mammals. No definite biochemical role has been ascribed to carnosine (beta-alanyl histidine) even though it has been known for over sixty years. Homocarnosine (gamma-aminobutyryl histidine) is relatively new. Obviously the physiological function of this dipeptide has not yet been ascertained.

2

The presence of these compounds in the brain argues for a definite function. In accordance with this invention it has been found that homologs of carnosine afford extremely satisfactory degrees of protection against cocci and bacilli infections. Thus homocarnosine possesses an anticoccic activity unshared by lower homologs. Carnosine, which differs from homocarnosine only by having one less carbon atom, is unsatisfactory in building resistance to coccic infections. According to another aspect of the invention two homologs of carnosine higher than homocarnosine are also desirable antimicrobials. These are also new compositions of matter, being the subject of copending application Ser. No. 831,741, filed June 9, 1969. Thus although the physiological function of homocarnosine is still speculative, and its higher homologs unknown, according to the practice of this invention, we have discovered its unique activity against bacterial infections.

DETAILED DESCRIPTION OF THE INVENTION

The processes of infection leading to disease are accepted to be a problem in the ecology of the parasite. It is being increasingly realized that the bacterial and host determinants are closely interrelated. Staphylococcal virulence derives from the combined action of several bacterial factors whose effectiveness is conditioned by the reactions of the host. Perhaps the most striking feature of host-parasite relationships in staphylococcal infections is the relatively atypical immunologic response. Human studies have given convincing evidence that most adult humans possess an array of antibodies against staphylococci. Nevertheless resistance to staphylococci seems to be governed to a considerable extent by other unrelated factors. For this reason attempts at prophylactic administration have not been completely successful.

By the practice of this invention there is provided a method of protecting mammals against bacterial infections. In accordance with the invention an antibacterial amount of certain dipeptides of histidine is administered to mammals in need of an antimicrobial effective in protecting against cocci and bacilli. The dipeptides administered for the control of bacterial infections are gamma-aminobutyrylhistidine (homocarnosine), and two new compounds, delta - aminovalerylhistidine and epsilon-aminocaproylhistidine. Whereas the dipeptide per se can be used, it will usually be administered as an edible salt such as delta-aminovaleric acid chloride, epsilon-aminocapric acid phosphate, homocarnosine gluconate, homocarnosine lactate, homocarnosine salicylate, homocarnosine carbonate, homocarnosine fluoride, homocarnosine iodide and the like. The salt is administered to mammals in pharmaceutically effective amounts, in the range of 150 to 250 milligram doses. The salts are easier to purify than the free dipeptide, and hence are more readily available in this form. In addition the salts are much more water soluble and will have lower pH values than the dipeptides themselves.

The high degree of resistance to staphylococcal infections obtained by the prophylactic administration of homocarnosine will be first demonstrated. This will be apparent from its biological effects in *in vivo* studies.

Swiss albino mice, 12 to 14 weeks old, and weighing approximately 20 to 25 grams each, were used in most of this work. Results showed that animals of either sex give comparable results and hence in these studies the animals were generally not screened according to sex.

The challenge organism was the penicillin-resistant *Staphylococcus aureus* (named Original), a strain maintained in our laboratories for years. It is preserved in the lyophilized state and stored at 0° C. and stock cultures were raised on Staphylococci medium no. 110 Difco slants

once in every 6 months. For testing, the inoculum was prepared from 24 hour cultures on said slants at 37° C. The cells were washed and suspended in physiological saline (TC Tyrode Solution, Difco). In contrast to conventional procedures, an LD 80-90 instead of LD 50 was used in these investigations. This has been the practice in our laboratories in studies with staphylococci since lower dosages often fail to give adequate degrees of mortality. The LD 80-90 was determined by injecting groups of mice subcutaneously in the groin area with different dilutions of the bacterial suspension and noting the mortality over a 5-day period.

Homocarnosine sulfate purchased from biochemicals manufacturers was used in all of the work reported herein. It was injected subcutaneously as a one percent solution in dosages indicated in each test. Investigations established a definite antistaphylococcal activity for homocarnosine. Because of its relative molecular simplicity and the commercial availability, an intensive study of this dipeptide was undertaken. To begin with, a series of prophylactic tests were done in which each animal was given 5 mg. of homocarnosine sulfate in 3 days by the subcutaneous route. On the 4th day (24 hr. after the last administration) the mice were challenged with *Staph. aureus* using control groups for comparison. Table 1 summarizes the results of 25 experiments in which the mortalities of the treated mice ranged from 0 to 30 percent.

TABLE 1
Prophylactic:subcutaneous

Group	Dose per mouse in mg.	No. of expts.	No. of animals	Percent mortality in 5 days
Control		25	247	84
Homocarnosine	5	25	335	20

During these studies it was noticed that commercially available homocarnosine was not always homogeneous in biological activity and physical appearance. The best samples were found to lower mortalities to 0 to 10 percent. Each sample was separately assayed before being used in animal tests.

Once the antistaphylococcal property was established, it was important to determine the appropriate dose for optimum results. In all tests thus far, an arbitrary dose of 5 mg. per animal was used. Three groups of animals were now treated prophylactically in 3 days by the subcutaneous route as before with 5 mg., 2.5 mg. and 1.5 mg. of homocarnosine sulfate per animal. The extent of protection given by the respective dose can be seen in the results after challenge reproduced in Table 2.

TABLE 2
Dose determination:prophylactic

Group	Dose per mouse in mg.	No. of animals	Percent mortality in days post-challenge				
			1	2	3	4	5
Control		10	70	80	80	80	90
Homocarnosine	5	20	0	5	5	5	5
Do.	2.5	20	10	10	10	10	10
Do.	1.5	10	10	20	20	20	20

The work set forth in Table 2 suggests that even with 1.5 mg. per animal prophylactically, the protection against subsequent challenge is comparable with that of higher doses used before. However, in view of the variations in results obtained with higher doses and the possibility of having a certain proportion of the sample in an inactive form, it was thought desirable to continue to use the 5 mg. dose in these investigations. Besides, there was no indication of any toxicity at this dose which further favored this dose for routine use.

In tests thus far, the animals were challenged within 24 hours after the termination of treatment and hence all

the data refer only to the protection within this narrow range of time. It was of interest to ascertain whether the resistance induced by homocarnosine is short-lived or long-lasting. A group of 50 mice were treated with homocarnosine (5 mg. per animal) in 3 subcutaneous injections. They were divided into 5 groups and each group was challenged with *Staph. aureus* at weekly intervals, using a fresh set of controls each time. The first group was challenged 24 hours after the last treatment as before. Mortalities in each group were recorded over periods of 5 days (Table 3).

TABLE 3
Duration of protection:prophylactic

Group	No. of animals	Percent mortality in days post-challenge				
		1	2	3	4	5
Challenged 24 hours after treatment						
Control	10	70	70	70	80	80
Homocarnosine	10	0	0	0	10	10
Challenged 7 days after treatment						
Control	10	70	80	80	80	90
Homocarnosine	10	0	0	0	0	0
Challenged 14 days after treatment						
Control	10	70	90	90	90	90
Homocarnosine	10	20	20	20	20	20
Challenged 21 days after treatment						
Control	10	60	70	70	70	70
Homocarnosine	10	0	30	30	30	30
Challenged 28 days after treatment						
Control	9	67	78	78	78	78
Homocarnosine	9	22	22	22	22	22

Although there is a slight drop in the degree of protection with the lapse of time, the results indicate that homocarnosine by itself is able to protect mice against experimental staphylococcal infections at least up to a period of 1 month. It is clear from Table 3 that even in the last group challenged 28 days after treatment, the degree of protection is comparable with results in many past experiments on immediate effects.

As a corollary to the observations on the duration of protection, it was of interest to ascertain the minimum time after administration, required for homocarnosine to express its activity. Fifty animals were treated with 5 mg. homocarnosine each, in one subcutaneous injection. They were divided into 5 groups of 10 each and successive groups were challenged at intervals of 1 hour using a different control group each time. A fresh inoculum from a 24 hour culture was also used each time. Mortality in each group was recorded and compared against that of the control group as can be seen in Table 4.

TABLE 4
Minimum time for expression

Group	No. of animals	Percent mortality in days post-challenge				
		1	2	3	4	5
Challenged 1 hour after treatment						
Control	10	50	60	60	60	60
Homocarnosine	10	20	20	20	20	20
Challenged 2 hours after treatment						
Control	10	40	50	50	50	60
Homocarnosine	10	20	30	30	30	30
Challenged 3 hours after treatment						
Control	10	50	60	60	60	60
Homocarnosine	10	20	20	20	20	20
Challenged 4 hours after treatment						
Control	10	30	60	60	60	60
Homocarnosine	10	10	10	20	40	40
Challenged 5 hours after treatment						
Control	10	50	50	50	50	50
Homocarnosine	10	10	10	10	10	10

Although the group challenged at 4 hours shows some inconsistency, it is evident that even as early as 1 hour after treatment, homocarnosine is able to express its anti-staphylococcal property. In fact, the degree of protection compares well with that after 5 hours.

Staphylococcal infections are known to recur. It was, therefore, of interest to see whether the survivors from the lethal challenge after prophylactic administration of homocarnosine are immune to rechallenge and if so to what extent. Rechallenge experiments were performed at varying intervals after the first challenge up to a maximum of 59 days, and it was consistently observed that the survivors were almost completely immune at least up to the periods covered, as set forth in Table 5.

TABLE 5
Survivors rechallenged 59 days after the first challenge

Group	No. of animals	Percent mortality in days post-challenge				
		1	2	3	4	5
Control.....	10	100	100	100	100	100
Survivors from homocarnosine.....	8	0	0	0	0	0

The results of in vivo experiments prompted experiments to study any direct effects of homocarnosine on the infecting organism itself. This was thought to be of value in attempting to explain the mechanism of action of this peptide. Emphasis was mostly on effects on growth pigmentation and the biochemical characteristics like the fermentation of mannitol, liquefaction of gelatin and the production of coagulase and DNase. An aqueous solution of homocarnosine (1 mg./ml.) was prepared and for each test 1 ml. of this was added to 4 ml. of the growth medium which varied depending upon the specific test. For chromogenesis and coagulase SA 110 (Difco) was used while Phenol Red Mannitol Agar (Difco) and Nutrient Gelatin (Difco) served as the test media for mannitol fermentation and gelatin liquefaction, respectively. DNase Agar (Difco) was used for DNase production. From these tests it was found that incorporation of homocarnosine into a growth medium, does not in any way alter the basic characteristics of the organism, nor does it affect the rate of growth. Filter paper discs soaked in homocarnosine solution placed on plates inoculated with *Staph. aureus* do not show any inhibition or enhancement of growth in their vicinity. Even when the same clone was continuously exposed to homocarnosine by maintenance on nutrient agar containing homocarnosine sulfate (1 percent by weight) for 20 subcultures at intervals of 3 days each, no significant changes were noticed.

Since homocarnosine is a dipeptide of gamma-aminobutyric acid and L-histidine, it was decided to compare the activity of homocarnosine with both the components when administered in equimolar ratios. The results of this work are recorded in Table 6.

TABLE 6
Homocarnosine and mixture of L-histidine and gamma-aminobutyric acid:prophylactic

Group	Dose per mouse in μ M	No. of animals	Percent mortality in days post-challenge				
			1	2	3	4	5
Control.....		10	90	90	90	90	90
Gamma-aminobutyric acid-L-histidine.....	+15+15	10	70	70	80	80	80
Homocarnosine.....	15	10	20	20	20	20	20

These data clearly indicate that while homocarnosine is effective in providing protection against the infection, the components gamma-aminobutyric acid and L-histidine in combination (simulating the relative ratios in the whole peptide) are essentially ineffective. Under these testing conditions the animals seemed not able to conjugate the components into homocarnosine.

Since it became apparent that homocarnosine was consistent in giving protection against subsequent challenge with *Staph. aureus*, it was decided to compare this with L-carnosine administered as before. Results after challenge are given in Table 7.

TABLE 7
Carnosine—prophylactic—subcutaneous—Swiss mice

Group	Dose per animal in mg.	No. of animals	Percent mortality in days post-challenge				
			1	2	3	4	5
Control.....		10	50	70	80	80	90
L-carnosine.....	10	10	70	100	100	100	100
Homocarnosine.....	5	10	20	30	30	30	30

These data further confirmed a definite value of homocarnosine in protecting Swiss albino mice against experimental staphylococcal infections. An analysis of the results of several experiments by this testing procedure revealed that experimental groups of Swiss mice given L-carnosine were not protected against the infection. Carnosine shows some effectiveness in C3H mice. However as can be seen in Table 8 homocarnosine is nevertheless much more effective. Then animals were used in each group, tested against *Staphylococcus aureus*.

TABLE 8
Carnosine—prophylactic—subcutaneous—C3H mice

Group	Dose per animal in mg.	Percent mortality in days post-challenge				
		1	2	3	4	5
Carnosine.....	10	40	40	40	40	40
Homocarnosine.....	10	0	0	0	0	0
Control.....		60	80	80	80	80
Carnosine.....	2.3	10	20	30	30	30
Homocarnosine.....	3.4	0	0	0	0	0
Control.....		80	90	90	90	90

whereas there are some differences as a result of host differences, homocarnosine is very effective in both strains of mice.

The value of homocarnosine in protecting mice against staphylococcal infections having been definitely established, data showing the antistaphylococcal activities of delta-aminovalerylhistidine (DAV-his) and epsilon-aminocaproylhistidine (EAC-his) will now be given. Homocarnosine is unique in its activity. As is apparent from the foregoing tables, the administration of homocarnosine induces resistance to staphylococcal infections at least up to a period of one month if not longer. Particularly significant is the complete immunity to reinfection of up to two months after an infection preceded by a homocarnosine treatment. This period is perhaps longer than any reported so far with any immunizing procedure of which we are aware. The two dipeptides delta-aminovalerylhistidine (DAV-his) and epsilonaminocaproylhistidine (EAC-his) also constitute significant new antimicrobials. The excellent protection conferred by these two dipeptides is illustrated by the data in Table 9. Here the drug was given in 2 equal doses, $\frac{1}{2}$ given 2 hours before infection with *Staphylococcus aureus* and $\frac{1}{2}$ given 4 hours after infection.

TABLE 9
Dipeptides—prophylactic—subcutaneous—Swiss mice

EAC-his.....	5	10	0	0	0	0
Control.....		50	70	80	80	80

It can be seen that by the practice of this invention staphylococcal infection will be reduced by administering a pharmaceutically effective amount of the dipeptide internally to the animal suffering from the infection. Similar results are obtained in the case of bacilli infections as will now be illustrated in the case of *Salmonella* old received 5 mg. of homocarnosine sulfate subcutaneously for 3 or 5 consecutive days, a total of 15 or 25 mg. Two or three hours after the final dose of homocarnosine the mice were given a subcutaneous challenge of an LD₅₀ dose of *Salmonella typhi*. The resulting mortalities at 72 hours after challenge are given in Table 10 which summarizes four experiments.

TABLE 10

Control.....	10	.....	70
Homocarnosine.....	10	15	40

The compositions of this invention thus constitute significant new antimicrobials. It is contemplated that they will be taken prior to periods where contact with staphylococci, streptococci or *Salmonella typhi* infections are likely, such as prior to entering a hospital. They can be taken orally in 250 to 500 mg. tablets or as injections of, say, 150 to 500 mg. The dipeptide per se or the sulfate, chloride or other edible salt thereof can be combined with an aqueous, vegetable oily, monoglyceride or diglyceride vehicle for injection, sodium chloride being used if necessary to render the solution isotonic. The solution will contain 0.1 to 5 percent, preferably 0.1 to 1.5 percent by weight, of the dipeptide or soluble salt thereof.

In the case of tablets the dipeptide may be preferred to the salt. Suitable colorants, adhesives, and lubricants will be incorporated in the tablets along with a solid pharmaceutical diluent, for instance, starches, lactose, sucrose and other pharmaceutical diluents. These tablets will contain 0.08 percent to 5 weight percent of the dipeptide, preferably 0.08 percent to 1.3 weight percent. Generally the same quantity will be used in all instances where quantities have been given, whether the dipeptide or the salt thereof is employed. Capsules can also be made. Oral administration is illustrated by the following results, set forth in Table 11. The dipeptide used was homocarnosine. Each animal (Swiss mice) received a total dose of 10 mg. of homocarnosine sulfate as an aqueous solution of 20 mg. Homocarnosine sulfate per ml. in water according to the schedule in the table. The control group received only the *Staph. aureus* injection.

TABLE 11

Administration schedule

1. 5 mg. orally (0.25 ml.)
2. 6 hrs. later, challenge with *Staph. aureus* subcutaneously
3. 6 hrs. later, 5 mg. (0.25 ml.) orally

Test results

Group	No. mice	Dose, mg.	Hours post-challenge				Percent mortality
			24	48	72	96	
Control.....	10	0	60	70	70	70	60
Homocarnosine.....	8	10	0	0	0	0	0

A process is thus provided for the control of infections in humans and other mammals due to cocci and bacilli, which involves administering to the mammal suffering from the infection an effective amount of the dipeptide or the edible salt thereof. In addition variations and modifications will occur to those skilled in the art. Thus an inoculum can be made from the serum of mammals which have recovered from the infection. This is illustrated as follows.

Mice which had received a total of 5 mg. of homocarnosine subcutaneously over a three day period were inoculated subcutaneously with an amount of *S. aureus* normally sufficient to kill 80-90 percent of the animals. Mice which recovered from the infection after this treatment were bled to death by orbital bleeding. All the blood was pooled in centrifuge tubes and allowed to clot for about 30 minutes. After loosening the clot it was centrifuged for 12 minutes at 1700 r.p.m. and the clear supernatant serum was carefully drawn off with a sterile Pasteur pipette. The serum was sterilized by passage through sterile millipore filters and stored in serum bottles at 10° C. for not more than 10 days.

An experimental group of 14 mice were each given 0.2 ml. of serum intravenously through the tail vein. A control group of 10 mice received the same volume of physiological saline solution. All mice were challenged subcutaneously 24 hours later with a lethal dose of *S. aureus*. The results are shown in Table 12.

TABLE 12

Serum

No. of mice	Percent mortality at days post-challenge				
	1	2	3	4	5
Control.....	10	90	100	100	100
Experimental.....	14	50	57	64	71

It will be seen that the serum protected nearly half of the mice after one day and about a third of the mice over the five-day period. This effectiveness will be improved by further studies of variables such as dose of homocarnosine, pattern of homocarnosine dosage, dosage of serum, time interval between serum administration and challenge infection, and stability of serum. Such ramifications are deemed to be within the scope of this invention.

What is claimed is:

1. A method of treating bacterial infections in mammals comprising administering to a mammal suffering for said bacterial infection an antibacterial effective amount of a dipeptide selected from the group consisting of gamma-aminobutyrylhistidine, delta-aminovalerylhistidine and epsilon-aminocaproylhistidine.
2. The method of claim 1 wherein the dipeptide is gamma-aminobutyrylhistidine.
3. The method of claim 1 wherein the dipeptide is delta-aminovalerylhistidine.
4. The method of claim 1 wherein the dipeptide is epsilon-aminocaproylhistidine.
